UNITED STATES PATENT OFFICE.

JUSTUS R. KINNEY, OF BOSTON, MASSACHUSETTS.

AIR-MOTOR.

1,123,311.

Specification of Letters Patent.

Patented Jan. 5, 1915.

Application filed June 26, 1913. Serial No. 776,434.

To all whom it may concern:

Be it known that I, JUSTUS R. KINNEY, a citizen of the United States of America, and a resident of Boston, in the county of 5 Suffolk and State of Massachusetts, have invented certain new and useful Improvements in Air-Motors, of which the following is a specification.

This invention relates to air motors and 10 particularly to that type of motors in which a piston is reciprocated by a supply of compressed air intermittently admitted to the piston chamber.

The main object of the invention is to 15 reorganize and improve the construction of a motor of this character, and to provide such a motor which will be cheap to manufacture, efficient in operation, and not liable to get out of order in continued use.

20 The invention consists in a plurality of standards from which oscillating cylinders are suspended, each cylinder being provided with two side ports one of which is adapted to register with an inlet port in said stand- 25 ard during the movement of said cylinder in one direction while the other port is adapted to register with the outlet port in said standard during the movement of said cylinder in the opposite direction.

30 The invention further consists in certain novel features of construction and arrangement of parts which will be fully understood by reference to the description of the drawings and to the claims hereinafter given.

35 Of the drawings: Figure 1 represents a horizontal section of a motor embodying the principles of the present invention, the cutting plane being on line 3—3 on Fig. 3. Fig. 2 represents a vertical section of the 40 same, the cutting plane being on line 2—2 on Fig. 3. Fig. 3 represents a transverse section of the same, the cutting plane being on line 1—1 on Fig. 2, and Fig. 4 represents a partial section, the cutting plane 45 being on line 4—4 on Fig. 1.

Similar characters designate like parts throughout the several figures of the drawings.

In the drawings, 10 represents the base

of the casing 11. This casing is provided 50 at opposite ends with removable plates 12, each provided with a bearing 13 in which is adapted to rotate the crank shaft 14. The shaft 14 has formed therein a plurality 55 of cranks 15, each connected by the link 16 with the piston 17 to which it is rigidly secured. Each piston is adapted to reciprocate in a cylinder 18 threaded or otherwise secured to a cylinder head 19. Each cylinder head 19 is provided with a cylindrical opening extending transversely there- 60 of, through which extends a cylindrical member or rod 20. This rod 20 extends through the upper ends of a plurality of standards 21 secured by the bolts 22 to the 65 flanged upper end of the casing 11. The upper end of the casing 11 is open as shown in Fig. 3 of the drawings. It is obvious that the cylinders 18 are suspended from the rod 20 and are adapted to oscillate about 70 the axis thereof during the rotation of the crank shaft 14. While in the drawings three cylinders 18 are shown it is self-evident that a greater number may be used if desired, the cranks connected to the pistons 75 in these cylinders being equally distributed about the axis of the crank shaft 14.

The upper ends of the standards 21 are provided with bearing faces contacting with similar bearing faces formed upon the cylinder heads 19, said bearing faces being held in contact by means of the nuts 23 threaded to the ends of the rod 20. Each cylinder head is provided with two pas- 80 sages 24 and 25 communicating with the 85 interior of the cylinder and having ports 26 and 27 in one bearing face of said head. The ports 26 and 27 are horizontally aligned immediately below the axis of the rod 20 when the cylinder 18 is in vertical position. 90 The bearing face of each standard 21 opposite the ported bearing face of each cylinder head 19 is provided with an inlet port 28 and an outlet port 29, said ports being hori- 95 zontally aligned immediately above the axis of the rod 20. The port 28 communicates by means of a passage 30 with an inlet pipe 31 from any suitable supply of compressed

air. The outlet port 29 communicates by means of a passage 32 with a discharge pipe 33.

It is obvious from an inspection of the drawings that when the cylinder 18 is in vertical position the various ports 26 and 27, 28, and 29 will be closed by means of the opposed bearing faces and all communication with said cylinder will be cut off.

10 When, however, the cylinder 18 is in the position indicated by the dotted lines *a* in Fig. 3 of the drawings, the ports 26 and 28 will be in register so that compressed air may enter from the inlet pipe 31 into the interior of the cylinder 18 and force the piston 17 therein downwardly, thus rotating the crank shaft 14, and during this movement the ports 26 and 28 are gradually closed until a complete cutoff is obtained when the

20 crank 15 reaches its lowermost position. As the crank shaft 14 continues to rotate and the piston 17 is moved in the opposite direction the ports 27 and 29 are gradually brought into register and the air in said cylinder 18 is forced therefrom into the discharge pipe 33. At this time the cylinder 18 will be in the position indicated in Fig. 3 by the dotted lines *b*. When in this position the outlet ports are fully opened and

25 the further movement of the crank into its upper vertical position will gradually cut off the outlet ports, the full cutoff being completed when the crank reaches said upper position. Further movement of the 35 crank will cause the inlet ports 26 and 28 to gradually register until the full opening is secured when in the cycle of the crank the cylinder again reaches the position indicated by the dotted lines *a*.

40 It is obvious from an inspection of the drawings that the inlet port of one of the cylinders 18 is always open so that when it is desired to operate the motor by opening a valve (not shown) in the pipe 31 the air under pressure may be admitted to this cylinder causing an initial rotation to the crank shaft, this rotation causing the movement successively of the other cylinders into a 45 position where the inlet valves thereto will be uncovered to permit the admission of air to said cylinders, thereby continuing the rotation of said crank shaft.

It is self-evident that the ports in each cylinder head 19 are located one on each side 55 of a vertical line through the center of the rod 20, on which said cylinders swing, and when said cylinders are on one side of said vertical line, compressed air may be admitted thereto, while, when on the other side 60 of said vertical line, the admission of air is cut off and the exhaust ports are opened.

65 This makes a very simple construction of motors in which the parts are reduced to a minimum without in any manner reducing the efficiency of the device.

It is believed that the operation and many advantages of this invention will be fully understood from the foregoing description.

Having thus described my invention, I claim:

1. In a device of the class described, the combination of two standards separated at their upper ends, one of which is provided with an inlet passage and an outlet passage communicating with ports in a side face thereof; a suspended cylinder having a side face thereof adapted to oscillate in contact with the ported face of said standard and having ports in said contacting face normally out of register with those in said standard; a reciprocating piston in said cylinder, and means for taking up the wear in said contacting side faces. 70 75 80

2. In a device of the class described, the combination of two standards separated at their upper ends, one of which is provided with an inlet passage and an outlet passage communicating with horizontally aligned ports in a side face thereof; a suspended cylinder adapted to oscillate about an axis immediately below the line of said ports, and provided with horizontally aligned ports immediately below said axis adapted to oscillate therewith and intermittently register 90 95 with the ports in one of said standards; a reciprocating piston in said cylinder; and means for oscillating said cylinder.

3. In a device of the class described, the combination of an oscillating cylinder the head of which is provided with a broad flat face parallel with the axis of said cylinder, said face being provided with two ports communicating with the interior of said cylinder; a standard for said cylinder provided with a broad flat face contacting with the ported face of said cylinder and having two ports therein normally out of alignment with the cylinder ports, one of said standard ports communicating with an inlet passage and the other with an exhaust passage; a reciprocating piston in said cylinder; means for oscillating said cylinder and its broad flat ported face in contact with the flat ported face of a standard to cause its ports to register alternately with the inlet and exhaust ports of said standard; and means cooperating with said standard for retaining said ported faces in contact. 100 105 110 115

4. In a device of the class described, the combination of an oscillating cylinder; a valve member on the cylinder having ports opening through a surface perpendicular to the axis of oscillation; a stationary valve member having ports opening through a similar surface and in contact with which said piston valve member is adapted to oscillate; and means for taking up wear between said surfaces. 120 125

5. In a device of the class described, the 130

combination of a rod; a plurality of cylinders mounted to oscillate about the rod; a support for said rod adjacent each cylinder; a valve member on each cylinder having 5 ports opening through a surface perpendicular to said rod; a similar coating valve member on each support and in contact with which said piston valve member is adapted

to oscillate; and means on the rod for forcing the cylinders and supports together. 10

Signed by me at 100 Boylston St., Boston, Mass., this 13th day of June, 1913.

JUSTUS R. KINNEY.
